UNITED STATES PATENT OFFICE.

BOUDEWIJN B. NEUTEBOOM AND CECIL HAMELIN TAYLOR, OF DETROIT, MICHIGAN.

INTERNAL-COMBUSTION ENGINE.

1,117,427.

Specification of Letters Patent. Patented Nov. 17, 1914.

Application filed July 15, 1912. Serial No. 709,320.

To all whom it may concern:

Be it known that we, BOUDEWIJN B. NEUTEBOOM, who is a subject of the Queen of the Netherlands, and CECIL HAMELIN TAYLOR, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

Our invention relates to internal combustion engines and an object of our improvements is to provide an improved engine which may be easily and accurately made and assembled.

We attain this object in the device illustrated in the accompanying drawings, in which,

Figure 1, is an end view of an internal combustion engine embodying our invention. Fig. 2, is the cylinder and crank case casting in end elevation, a part being broken away also showing the magneto and its mounting, the magneto support is sectioned 30 on the line 2 Fig. 3. Fig. 3, is a side elevation of the magneto with its support shown in section in the plane indicated by the line 3—3 Fig. 1, the circulating pump and its support also being shown in section. Fig. 35 4, is an end elevation of the parts shown in Fig. 3, the pump and magneto being removed.

A A A is an integral casting of the cylinder and crank case of an internal combustion engine.

B, is a bracket cast integral with A and extending laterally therefrom.

C, is the shelf supported by and cast integral with the bracket B. There is an opening a in the crank case concentric with the position occupied by the main shaft of the engine and there is an opening b in said casting concentric with the position occupied by the cam shaft. The bracket C has ribs C¹ and C² cast at its upper surface and these ribs are formed in the arc of a circle z z Fig. 2 whose center is at the center that shall be occupied by the shaft of the magneto. The axes of the openings a and b and 55 the circle z z are parallel to each other and

are so located that gear wheels H I and K Fig. 1 located respectively on the shafts of the magneto, the counter, or cam shaft and the main shaft of the engine, may gear with each other as shown in dotted lines in Fig. 1. 60

E, is a magneto and D is a block or shim having its upper surface flat to fit against the base of the magneto and its under surface curved in the arc of a circle z z so as to fit against the corresponding surface of the shelf C.

e e are bolts which pass through openings in the shelf C, their threads engaging threads in the base of the magneto E so as to secure said magneto in place.

Of course, instead of having a shim D the base of the magneto might be formed to fit the surface of the shelf C, or the faced off ribs C¹ C².

By this construction the casting A may be 75 set once for all in the machine tool and surfaces concentric with the position of the main shaft and with the cam shaft finished off and the ribs C¹ C² on the shelf C accurately turned concentric with the position 80 occupied by the magneto shaft. By this construction extreme accuracy is not required in positioning the magneto on its support as any variation would be in a circle concentric with the magneto shaft and 85 the meshing of the gear H with the gear I will not be disturbed thereby.

F, is a partly annular projection formed integral with and extending from the casing A and forming a continuation of the curved 90 inclosing wall of the casing of the gears K and J. This projection F forms the curved wall of a casing concentric with the shaft of the magneto E.

H, is a gear wheel on the shaft G of the 95 magneto.

M, is a sheet metal disk formed to close one end of the casing inclosing the gear wheel H, of which casing F forms the curved wall.

N, is a sheet metal stamping in approximately the form of a disk lying against the edge of the projection F and inclosing the other end of the casing of which said projection forms the curved wall.

O, are bolts having cylindrical bodies and concentric screw threaded portions extending in opposite direction from said cylindrical bodies and of less diameter than said bodies. Each of the bolts O has one of its 105 110

screw threaded shanks extending through a hole in the disk N, its threads engaging threads in a hole in a lug f extending from the projection, and its larger cylindrical part acting to hold the disk N in place.

- 5 P, is a casting forming the main portion of the casing of a centrifugal circulating pump. From the casting P extend ears p p p which are provided with apertures 10 which pass over the outer screw threaded shank of the bolts O and lie against the cylindrical portion of said bolts. The casting P is secured in place and spaced from the projection F by the bolts O with their nuts 15 v v v.

S, is a cap fitting upon the circular edge of the casting P to complete the inclosing casing of the pump.

- Q, is a hollow cylindrical arbor fixed at its 20 outer end in the cap S and extending inward through the casing P S axially in line with the shaft G of the magneto E.

R, is the rotor of the pump having the ways r r therein.

- 25 T, is a cylindrical arbor extending from the rotor R concentric therewith through the casting P.

The rotor R has a cylindrical opening through its center which fits upon the arbor 30 Q so that the rotor turns upon said arbor.

t, is a cylindrical plug fitting into the opening in the arbor T.

- h, is a pin extending transversely through the arbor T and the plug t holding the latter in place, its ends projecting and engaging slots g g in the walls of the hollow cylindrical projecting hub of the gear wheel H. The rotation of the shaft G carries with it the gear wheel H which acts upon the pin 40 h to turn the rotor R.

m, is a washer surrounding the arbor T between the faced off surfaces surrounding said arbor on the adjacent faces of the rotor R, and casting P.

- 45 U, is a plug fitting into the bore of the arbor Q and adapted to slide therein. The inner end of the plug U is formed into the shape of a portion of the surface of a sphere and bears against the plug t fixed in the 50 bore of the rotor R.

W, is a grease cup screwed into the cap S coaxially with the arbor Q, its interior com-

municating by an aperture n with the interior of said arbor.

V, is a compression spring located in the 55 bore of the arbor Q, one end bearing against the grease cup W and the other against the plug U. Thus the spring V acts to press the rotor firmly against the washer m and form a tight joint between said rotor and 60 the casting P.

q q are radial apertures through the walls of the arbor R through which grease or oil may pass from the cup W.

X, (Fig. 1) is the intake passage to the 65 pump opening into the cap S of the casing P S, and Y, is the exit passage opening at the periphery of the casting P.

What we claim is:—

1. In combination with an internal combustion engine, a shelf C having its upper surface formed in the arc of a circle in cross section, an auxiliary mechanism and a block B shaped to fit said surface, said auxiliary mechanism being adapted to be placed upon 70 said block.

2. In combination with an internal combustion engine, having a gearing, an auxiliary mechanism provided with a gear wheel adapted to engage said gearing, a shelf having 80 a surface formed in the arc of a circle in cross section, the center of said circle being upon the axis of said gear wheel, a block B shaped to fit said surface, said mechanism being secured upon said block. 85

3. In an internal combustion engine, the combination of a casting A, a shelf C mounted thereon having its upper surface formed in the arc of a circle, an auxiliary mechanism having a shaft, said mechanism being 90 mounted upon said shelf to engage said surface with its shaft at the center of the arc in which said surface is formed, a bracket F formed on said shelf, and a rotary pump secured on said bracket axially in line with the 95 shaft of said auxiliary mechanism.

In testimony whereof, we sign this specification in the presence of two witnesses.

BOUDEWIJN B. NEUTEBOOM
CECIL HAMELIN TAYLOR.
